CRUCIFIX OR SIMILAR ARTICLE

Anthony F. Sava, Brooklyn, N. Y.

Application July 2, 1953, Serial No. 25,770

Term of patent 14 years

(Cl. D29—23)

FIG. 1.

To all whom it may concern:

Be it known that I, Anthony F. Sava, a citizen of the United States, residing at Brooklyn, in the county of Kings, State of New York, have invented a new, original, and ornamental Design for Crucifix or Similar Article, of which the following is a specification, reference being had to the accompanying drawing forming a part thereof.

Fig. 1 is a front elevational view of a crucifix or similar article showing my new design; and

Fig. 2 is a side elevational view thereof.

I claim:

The ornamental design for a crucifix or similar article, as shown.
